UNITED STATES PATENT OFFICE.

JOSEPH MUSIL, OF CLEVELAND, OHIO.

CUFF-BUTTON.

1,317,722.

Specification of Letters Patent.

Patented Oct. 7, 1919.

Application filed March 29, 1919. Serial No. 285,994.

To all whom it may concern:

Be it known that I, JOSEPH MUSIL, a citizen of the United States, residing at Cleveland, in the county of Cuyahoga and State 5 of Ohio, have invented certain new and useful Improvements in Cuff-Buttons, of which the following is a specification.

This invention relates to cuff buttons and has for its object the provision of a button 10 of simple and inexpensive construction, capable of being used with equally good results on either soft or stiff cuffs and which will hold the ends of the cuff together without liability of the button becoming accidentally 15 detached therefrom.

The invention further aims to provide a cuff button which may be readily attached to or detached from a cuff and in which provision is made for preventing withdrawal 20 of the shank of the button through the buttonhole of the cuff after the ends thereof have been fastened.

The invention further contemplates providing the shank of the button with a holding member or catch movable in a plane at substantially right angles thereto and provided with a roughened finger-engaging surface so that by grasping said roughened surface and moving the member in one direction, the end thereof will be brought into alignment with the shank and permit the button to be removed from the cuff and by moving said member in the opposite direction the latter will extend across the button-hole and prevent withdrawal of the shank 35 of the button.

A still further object of the invention is generally to improve this class of devices so as to increase their utility, durability and 40 efficiency.

In the accompanying drawings:

Figure 1 is a perspective view of a cuff button embodying the present invention showing the same applied to a cuff of conventional form;

Fig. 2 is a perspective view of the cuff button detached;

Fig. 3 is a longitudinal sectional view showing the button locked in position on the 50 cuff;

Fig. 4 is a similar view showing the holding member or catch withdrawn to permit removal of the button from the cuff;

Fig. 5 is a transverse sectional view, taken 55 on the line 5—5 of Fig. 2;

Fig. 6 is a bottom plan view of Fig. 3.

Corresponding and like parts are referred to in the following description and indicated in all the views of the drawings by the same reference characters.

The improved cuff button forming the subject-matter of the present invention may be used in connection with either soft or stiff cuffs and by way of illustration is shown applied to a conventional form of soft cuff in 60 which 5 designates the body of the cuff and 6 the registering buttonholes therein.

The cuff button is preferably stamped, rolled, pressed or otherwise formed from a single sheet of metal and comprises a body 65 portion having one end thereof bent to produce a flat head 7 adapted to be positioned on the outside of the cuff, the metal at one end of the head being bent upon itself at 8 and thence extended inwardly in contact 70 with the lower face of the head to a point adjacent the medial line thereof, the metal being thence bent downwardly at substantially right angles to the head to form a connecting web or shank 9 preferably extending the entire width of said head and terminating in a lateral extension, indicated 75 at 10. The extension 10 is preferably disposed parallel with the head 7 and is projected longitudinally beyond the rebent portion 8 thereof to form a support for a holding member or catch 11.

The extension 10 is provided with a longitudinal slot 12 defining spaced stop shoulders 13, the side walls of the slot being undercut, as indicated 80 at 14, for engagement with the correspondingly beveled edges of a guide block 15. The guide block 15 may be riveted, soldered or otherwise rigidly secured to the upper face of the holding member 11, as indicated 85 at 16, and as the side walls of the block are undercut or beveled the holding member will be supported for sliding movement on the shank. The lower face of the holding member 11 is preferably provided with a 90 series of transverse serrations 17 to form a roughened finger-engaging surface when actuating the holding member to fasten or release the cuff button.

In applying the button to a cuff, the holding member or catch 11 is moved longitudinally of the extension 10 until one end thereof registers with the adjacent side face of the shank 9, and in which position the other end of the holding member will register 105 with the slot 12. The button is then 110 applied to the cuff and the holding member 11 is moved longitudinally until the shoulder 13 rests against the beveled edge of the guide block 15, the holding member 11 being held in this position by the transverse serrations 17.

ter with the free end of said extension. The button is then grasped by the head 7 and the extension 10 thereof inserted through the buttonholes in the cuff, as shown in full lines in Fig. 4 of the drawings, after which the head is pressed downwardly to the dotted line position shown in said figure and the holding member or catch moved longitudinally of the extension 10 until the end of 10 said holding member projects longitudinally beyond the shank of the button and in which position the button will be securely held against accidental displacement, as clearly shown in Fig. 3 of the drawings. 15 The length of the slot 12 is such that the guiding member or block 15 will abut against one of the shoulders 13 when the holding member is in extended position and abut against the other shoulder when the holding 20 member is in retracted position, thereby limiting the longitudinal movement of said holding member and retaining the parts in assembled position at all times. The edges of the extension and holding member are 25 preferably curved or rounded at 18 so as not to present any sharp edges which would tend to cut or tear the buttonhole when positioning the cuff button on or removing said button from a cuff. 30 It will here be noted that the upper surface of the guide block 15 is disposed flush with the upper surface of the extension 10 so as to present a smooth bearing surface for engagement with the inner face of the 35 cuff. It will also be noted that the length of the holding member is slightly less than that of the extension 10, while the upper surface of the free end of the extension and lower surface of the holding member are 40 inclined or beveled at 18' to facilitate inserting the parts through the buttonhole of a cuff. The head 7 of the cuff button may be highly polished to present a neat attractive appearance or a suitable initial or ornamental design engraved thereon if desired. 45 It will, furthermore, be understood that the cuff buttons may be made in different sizes and shapes and constructed of metal or any other desired material without departing 50 from the spirit of the invention.

Having thus described the invention, what is claimed as new is:

1. A cuff button including a head, a shank secured to the head and provided with a lateral extension having a longitudinal slot therein, and a holding member coacting with the head and having a guiding member projecting within the slot, said holding member being movable to inoperative position en-

tirely beneath the extension and to operative position with one end thereof projecting longitudinally beyond the shank. 60

2. A cuff button including a head having a shank provided with a lateral extension, and a holding member slidably mounted on the extension and movable to operative position with one end thereof extending longitudinally beyond the shank and coacting with the head and to inoperative position with the opposite ends of the holding member disposed entirely within the lines of said extension. 70

3. A cuff button including a head having a shank extending medially therefrom and provided with a lateral extension having a slot formed therein and extending longitudinally thereof, a holding member of less length than the extension slidably mounted thereon and provided with a guiding block extending within the slot, the opposite end walls of the slot forming stop shoulders for engagement with the adjacent ends of the block. 75

4. A cuff button including a head having a shank and provided with a lateral extension having a longitudinal slot, the side walls of which are undercut, a holding member of less length than the extension slidably mounted thereon and having its lower face roughened to form a finger-engaging surface, a guide block secured to the upper face of the holding member and having its side walls inclined for engagement with the undercut walls of the slot, the opposite end walls of the slot by engagement with the adjacent ends of the guide block serving to limit the longitudinal movement of the holding member with respect to the shank. 85 90 95

5. A cuff button formed from a single sheet of material having one end thereof bent to produce a flat head, the metal being thence bent upon itself at substantially right angles to the head to form a shank and thence bent laterally to produce an extension projecting longitudinally beyond one end of the head, 100 there being a slot formed in the extension, and a holding member slidably mounted on the lower face of the extension and provided with means projecting within the slot for engagement with the side walls thereof, 110 said holding member being movable to operative position with one end thereof projecting longitudinally beyond the shank and to inoperative position with the opposite end thereof disposed substantially flush with the 115 free end of the extension.

In testimony whereof I affix my signature.
JOSEPH MUSIL. [L. S.]
